ALFRED DUVALL, OF BALTIMORE, MARYLAND.

Letters Patent No. 86,290, dated January 26, 1869.

IMPROVEMENT IN SUBMARINE EXCAVATORS.

The Schedule referred to in these Letters Patent and making part of the same.

To all whom it may concern:

Be it known that I, ALFRED DUVALL, of Baltimore, in the county of Baltimore, and State of Maryland, have invented a new and useful Improvement in Machinery for Making Excavations under Water, and removing the same; and I do hereby declare that the following is a full, clear, and exact description thereof, reference being had to the accompanying drawings, and letters of reference thereon, making a part of this specification, in which—

Figure 1, plate 1, is a longitudinal section in elevation.

Figure 2, plate 1, a vertical section of journal-box of revolving excavator.

Figure 3, plate 1, a cross-section of same.

Figure 4, plate 2, a plan of bottom of boat; showing excavating-pipe, &c.

Figure 5, plate 2, a section of spring-swivel.

Figure 6, plate 2, a section of excavating-auger, through the largest diameter.

Figure 7, plate 3, a plan of deck of boat, showing carriage-way, ropes, directing-sheaves, capstans, swivels, and pump.

Figure 8, plate 4, a cross-section of boat, through the compound or internal hollow universal joint.

Figure 9, plate 4, a cross-section of boat, showing receiving-chamber, pump, and discharge-troughs or pipes, with flexible couplings.

Figure 10, plate 4, cross-section of compound or internal hollow universal joint.

Figure 11, plate 4, longitudinal section of same.

To enable others skilled in mechanics to make and use my invention, I will proceed to describe the construction and operation of the same.

I use a boat carrying a steam-engine or other motor, with the other appliances for the purpose intended, as described in this specification.

A is a centrifugal pump.

B is a short supply-pipe to the pump A.

C is an air-tight supply and receiving-chamber, with lids.

D is an outer box or water-chamber, surrounding and rising above the chamber C, to be filled with water, by which the chamber C is made air-tight.

E is a valve in the box D, intended to be closed when charging the pump A.

F is a screen in the chamber C, for collecting any particles too coarse to pass through the discharges of the pump A.

G is gearing for communicating motion to the shaft H and dredging-pipe J.

I is a compound or internal hollow universal joint, with journal-box, the construction of which is more fully shown by figs. 10 and 11, plate 4.

J is a dredging and supply-pipe to the chamber C and pump A.

K is a hollow, sectional excavating-auger, fastened

to the pipe J, a cross-section of which is shown by fig 3, plate 2.

L is a flange on the pipe J, against which the friction-rollers M in the journal-box N revolve, as shown by figs. 2 and 3, plate 1.

O are friction-rollers in the journal-box N, within which the pipe J revolves.

P are pins in the journal-box N, passing through the ends of the bail Q, by which the journal-box N and pipe J are suspended.

R are spring-swivels, as shown by figs. 4 and 5, plate 2, attached to the pins P.

S are rollers, in a line of the centre of the universal joint.

T are directing-sheaves, shown on fig. 7, plate 3.

U is a double-eccentric capstan, around which the ropes V, connected with the swivels R, and the ropes W, connected with the truck X, work, as shown by fig. 7, plate 3, the movement of which capstan to the right or left, moves the dredging-pipe J and truck X horizontally, as desired.

The spring-swivels R are intended to give elasticity to the wire ropes V, so as to compensate (when the pipe J is raised or lowered) for the difference between the chord and the arc of the rollers S, and the slight unequal movement in the eccentric-capstan U.

Y are directing-sheaves, over which the ropes W pass.

Z are plain swivels, attached to the truck X and ropes W, for tightening the same.

A' is a sheave in the truck X, over which the rope B' passes to the capstan C', by which the pipe J is lowered, the capstan C' having a ratchet and catch.

D' is a carriage-way, on which the truck X traverses.

The capstan U, as shown by the accompanying drawings, is a double eccentric, of different diameters and different centres, so that in its movement, either to the right or left, it will always keep the ropes V and W tight.

E' are discharge-troughs or pipes, either round, square, or any other shape, with leather or any other flexible couplings, F', which couplings are bolted to the troughs or pipes E', and to a series of trough or pipes, so as to be conveniently connected or disconnected, and making a tight joint.

Operation.

The boat, carrying the appliances for the purpose intended, being brought to the place of use, and secured in position, the pump A is charged, also the water-chamber D. The pump A is then set in motion, as also the excavating-pipe J, when, by means of hawsers, anchored or secured ahead, the boat is held in position and drawn forward in the line of excavation, as desired.

The auger K, attached to the end of the pipe J, as it revolves, excavates the earthy matter desired, which, in connection with the water, from the effect of the at-

mospheric pressure, is forced into the pump A, and by it is discharged into the trough E', and from which it is conducted off, through a series of troughs or pipes with flexible joints, to the point desired. If discharging over water for a long distance, and particularly if the water is agitated, I use pipes with flexible joints, supported on pontoons or lighters; and if discharging over land, I use pipes or open troughs, supported on movable trucks or trestles.

The operation of dredging being commenced, the pipe J is moved horizontally, as desired, by means of the capstan U, while it is moved vertically, as desired, by means of the capstan C, when, by means of the revolutions of the auger and movement of the pipe, as described, the auger will excavate a section of a sphere proportionate to the distance it is moved by the appliances, as described.

What I claim as my invention, and desire to secure by Letters Patent, is—

1. The compound or internal hollow universal joint I, with a journal-box, substantially as and for the purpose set forth.

2. In combination with the tube J, the journal-box N, constructed with friction-rollers M, substantially as set forth.

3. In combination with the tube J, the sectional hollow boring-head K, having cutting-lips, formed substantially as set forth.

4. The combination of the double-eccentric capstan U, with the ropes V and W, and the spring-swivels R and pipe J, substantially as set forth.

Witnesses: **ALFRED DUVALL.**
SAMUEL KEEN,
A. LESLIE DUVALL.
